UNITED STATES PATENT OFFICE.

TEOFIL N. MORGAN, OF DAYTON, OHIO.

SHOE.

Application filed January 16, 1926. Serial No. 81,842.

This invention relates to shoes.

The object attained in the invention is a shoe especially adapted for hard usage, as a rough walking shoe, farmer's and lumberman's shoe, steel mill and foundry worker's shoe, etc., the improved shoe being herein shown and described more particularly as moulder's shoe.

While the improved shoe is especially adaptable for wear under conditions of rough usage, it is nevertheless designed and made in an excellent style for general use.

The design of the improved shoe lends itself to low cost of production, it being composed of few and simple parts assembled on lines convenient for low cost manufacturing.

The shoe is especially designed to protect the ankles and the upper portions of the feet of the wearer by excluding the weather and the rough elements under foot when worn out of doors, to protect the feet of moulders from hot metal, the direct heat from furnaces, cupolas, etc., and generally to withstand rough conditions of wear.

In the accompanying drawings, the several parts of the upper part of the shoe are shown separately and also assembled before the sole is applied, the detail showing of the parts serving to illustrate the novel design of the parts which give effect in the shoe to its characteristic features and qualities.

In the drawings:

Fig. 1 is a diagram or plan view of the main or front upper of the shoe;

Fig. 2 is a detail view of an insert for the upper;

Fig. 3 is a perspective view of the complete assembly of the upper part of the shoe;

Fig. 4 is a perspective view of the completed shoe.

As here shown, the front upper 1 of the shoe including the rearwardly extended button or buckle flaps 2 is a single piece except as to the insert 3. The peculiar cutting of the main part 1 of the front upper, as illustrated in Fig. 1, adapts the part to be cut with the minimum waste of stock, the entire upper of the desired shape being then completed by the addition of the insert 3. The curved and diagonal cuts 4-5 on lines which define the top and the front medial line 3 respectively of the shoe present the space, when the part is folded on its front medial line, for the insert 3, the assembly of

the two parts being on lines which effect neatness of design and a construction well adapted in a shoe for rough wear. The seams 6 of the insert occur on lines which develop no weakness in the construction or discomfort to the wearer.

The rear uppers 7 of the shoe are in two pieces sewed together on a medial seam line 7^a at the rear of the shoe and to the front upper on opposite seam lines 8, thus presenting a space on each side of the shoe for an elastic 9 interposed between the uppers in the well known manner of the congress gaiter shoe.

Disposed over the elastic inserts 9 are opposite rearwardly extended cover flaps 10, terminating in the button flaps 2 and under cut as at 11 to give free action to the elastics, shield inserts 12 being arranged inwardly adjacent the under cut portions to more effectively close the overlapping joint.

The essential novelty of the construction as here shown consists in the peculiar cutting of part 1 with respect to effecting the contour of the front of the shoe, the shape including the cover flaps 10 and fastening flaps 2 being completed by the insert 3. It will be observed that the arrangement is effected with the minimum of material and a design which is neat and highly meritorious from the view point of utility. It will be noted that the entire construction consists of few parts and that it is free from multiple overlapping thickness of material, this having reference to the gaiter elastics and the single flaps which serve to cover the elastics and thus to protect the feet of the wearer under conditions herein pointed out.

Having described my invention, I claim:

1. A shoe including front and rear upper portions, elastics interposed on the opposite sides of the shoe between said portions, and covering portions for the elastics extended rearward from said front portion, said front portion having an insert joined thereto by a seam extended downward from the upper edge along the center line, thence laterally along the side, and thence upward and rearward to the upper edge of the shoe.

2. A shoe including front and rear upper portions, elastics interposed on the opposite sides of the shoe between said portions, undercut, rearward extended portions formed integral with said front portion, and shield inserts coacting with said rearward extended portions for covering the elastics, said

front portion having an insert joined thereto by a seam extended downward from the upper edge along the center line, thence laterally along the side, and thence upward and rearward to the upper edge of the shoe.

3. A shoe including front and rear upper portions, elastics interposed on opposite sides of the shoe between said portions, rearward extended covering portions of said front portion for the elastics including fas-

tening extensions adapted to be secured at the rear of the shoe, said front portion having an insert joined thereto by a seam extended downward from the upper edge along the center line, thence laterally along the side, and thence upward and rearward to the upper edge of the shoe. 15

In testimony whereof I affix my signature.

TEOFIL N. MORGAN.
